UNITED STATES PATENT OFFICE.

THOMAS J. MACDONALD, OF YONKERS, NEW YORK.

HAT FLANGING AND FINISHING MACHINE.

1,165,195.

Specification of Letters Patent. Patented Dec. 21, 1915.

Application filed June 18, 1915. Serial No. 34,819.

To all whom it may concern:

Be it known that I, THOMAS JOSEPH MACDONALD, a citizen of the United States, and a resident of Yonkers, in the county of Westchester and State of New York, have invented a new and Improved Hat Flanging and Finishing Machine, of which the following is a full, clear, and exact description.

The invention relates to hat flanging machines such as shown and described in the Letters Patent of the United States, No. 1,049,885, granted to me on January 7, 1913.

The object of the present invention is to provide a new and improved hat flanging and finishing machine more especially designed for flanging and finishing women's hats, and arranged to accommodate differently shaped hat blocks, to enable the operator to conveniently reach every part of the brim to properly set, flange and finish a hat.

In order to accomplish the desired result use is made of a standard, a table supported on the said standard, a plate mounted to swing on the said table to overlie the latter or to stand at a right angle to the table, a carrier mounted to turn on the said plate and having means for removably holding a hat block, locking means for locking the said plate when in horizontal position to the table, locking means for locking the said table when in vertical position to the said standard, and manually controlled releasing means mounted on the said standard for releasing either of the said locking means to allow of swinging the plate and with it the carrier from horizontal into vertical position and vice versa.

A practical embodiment of the invention is represented in the accompanying drawings forming a part of this specification, in which similar characters of reference indicate corresponding parts in all the views.

Figure 1 is a side elevation of the hat flanging and finishing machine with the carrier, block holder and hat block in horizontal position and with the lower portion of the standard shown in section; Fig. 2 is a plan view of the same with the carrier and parts mounted thereon in vertical position;

Fig. 3 is a rear side elevation of the upper portion of the standard, the table and carrier; Fig. 4 is a sectional side elevation of the hat flanging and finishing machine with the carrier in horizontal position; Fig. 5 is 55 a similar view of the same with the carrier in tilted position; Fig. 6 is a sectional side elevation of the upper portion of the standard and the locking device for locking the carrier when in vertical position to the 60 standard; Fig. 7 is a similar view of the same with the table in raised position to allow rotation thereof; Fig. 8 is an enlarged sectional plan view of the standard and part of the releasing lever for releasing the 65 locking device used for fastening the carrier to the table, the section being on the line 8-8 of Fig. 4; Fig. 9 is a sectional plan view of the locking device for locking the carrier to the standard; Fig. 10 is a sectional side elevation of the same on the line 10-10 of Fig. 9; Fig. 11 is a sectional plan view of the hat flanging and finishing machine on the line 11-11 of Fig. 1; Fig. 12 is an enlarged transverse section of the 75 locking device for locking the carrier to the table, the section being on the line 12-12 of Fig. 11; Fig. 13 is a perspective view of the slide for actuating the keeper of the fastening device shown in Figs. 11 and 12; 80 Fig. 14 is a plan view of one of the hat block holders; Fig. 15 is a sectional side elevation of the same on the line 15-15 of Fig. 14; Fig. 16 is a sectional side elevation of another hat block holder attached to the 85 carrier and supporting a hat block; Fig. 17 is a plan view of the same with a portion of the hat block broken out; and Fig. 18 is a reduced plan view of the hat flanging and 90 finishing machine and the power means for rotating the block carrier.

The hat flanging and finishing machine is mounted on a hollow standard A having a base A' adapted to rest on a floor or other suitable foundation. Into the upper end of 95 the standard A fits loosely a hub B' depending from a table B provided with pairs of depending lugs B² provided with transverse pivots B³ engaging lugs C' integral on the under side of a plate C provided at its mid- 100

dle with a pivot C^2 on which is mounted to turn loosely a carrier D , preferably in the form of a disk. On the top of the carrier D is secured a ring-shaped offset or pulley E on which is removably held a holder F for removably holding or supporting a hat block G . By the arrangement described the carrier D and the hat block holder F as well as the hat block G can be readily turned on the pivot C^2 , and by the use of the pivotal connection between the plate C and the table B the plate as well as the carrier D , the hat block holder F and the hat block G can be swung into either a horizontal position, as shown in Fig. 2 and in dotted lines in Fig. 1, or into a vertical position. It is understood that when the plate C is in horizontal position it overlies the table B and when it is in a vertical position it stands at a right angle to the said table B . By reference to Figs. 1, 4, 5 and 7 it will be noticed that the table B terminates at one side of the standard A to allow of swinging the plate C into vertical position with the plate then standing close to the standard A , as plainly shown in dotted lines in Fig. 1 and in Fig. 6.

In order to lock the plate C in place when in horizontal position, the following arrangement is made: On the under side of the plate C and, as shown in Figs. 4 and 7, at the left-hand side thereof, is secured a catch H adapted to pass through an opening B^4 formed in the table B to engage a keeper H' in the form of an arm mounted to swing on a pivot H^2 attached to the under side of the table B (see Fig. 11). The keeper H' is pressed on by a spring H^3 and is engaged by a pin I' projecting upwardly on a slide I mounted to slide longitudinally in guideways B^5 attached to or forming part of the table B . The slide I is provided with an opening I^2 into which projects the upper end J' of a lever J fulcrumed at J^2 on a bracket B^6 attached to or forming part of the guideway B^5 above mentioned. The lower end of the lever J is provided with a cam J^3 adapted to pass through one of a series of openings A^2 formed in the standard A a distance below the top thereof. A spring J^4 is interposed between the bracket B^6 and the upper end J' of the lever J to normally hold the latter in the position shown in Fig. 4, that is, to hold the slide I in outermost position and the keeper H' in engagement with the catch H , and to hold the cam J^3 within the standard A . When the parts are in this position the plate C is locked in horizontal position to the table B . When it is desired to unlock the plate C prior to swinging the same into vertical position, the following arrangement is made: In the standard A is mounted to slide vertically a plunger K resting at its lower end on the inner end L' of a treadle L fulcrumed at L^2 on the base A' and under the control of the operator's foot.

Normally the treadle L is held in uppermost position by the weight of the plunger K , but when the operator presses the treadle L the plunger K is lifted and in moving upward the plunger engages the cam J^3 and forces the same outward thus imparting a swinging movement to the lever J . The swinging movement given to the lever J causes an inward movement of the slide I so that the pin I' imparts an inward swinging movement to the keeper H' thus moving the same out of engagement with the catch H and thereby unlocking the plate C and allowing the same to swing into vertical position. When this has been done, the operator releases the treadle L so that the plunger K moves downward to normal position and out of the path of the cam J^3 so that the lever J is returned by the action of the spring J^4 and the keeper H' is returned to its normal position by its spring H^3 . It will be noticed that when the keeper H' is in the return position it can be readily reengaged by the catch H on swinging the plate C back into horizontal position on top of the table B .

In order to lock the plate C , and the parts carried thereby, to the standard A when the said plate is swung into vertical position, the following arrangement is made: On the under side of the plate C diametrically opposite the catch H is arranged a catch N having its base N' mounted to slide in a suitable guideway N^2 attached to the under side of the plate C . The catch N is adapted to engage one of a series of keepers A^3 formed on the standard A to lock the plate C in place when in vertical position (see Fig. 6). Springs O are attached to the brackets B^7 forming part of the table B , and the said springs O are adapted to be engaged at their free ends by bosses O' attached to the under side of the plate C when the latter is swung into vertical position and its catch N engages the keeper A^3 . When it is desired to release the catch N to permit of swinging the plate C and the parts carried thereby from vertical position back into horizontal position then the operator presses the treadle L to move the plunger K upward, which latter engages with its top the catch N and pushes the same upward in its guideway N^2 to disengage the catch from the keeper A^3 and to allow the springs O to start the plate C on the return swinging movement, as will be readily understood by reference to Fig. 5. As soon as the catch N has lifted the keeper A^3 it slides by its own weight back to outermost position so as to readily reengage the keeper A^3 on a return swinging movement to vertical position given to the plate C .

While using the machine, it is somewhat desirable to change the position of the table B relatively to the fixed standard A to suit the convenience of the operator, and for this

purpose the table B is adapted to be turned relatively to the standard A. For the purpose mentioned the table B is provided adjacent its hub B' with a number of apertures 8 B⁸ (see Fig. 2), the apertures being arranged in a circle concentric to the hub B' and the apertures are preferably placed equal distances apart. Any one of the apertures B⁸ is adapted to be engaged by a locking pin P 10 held on the outside of the standard at the upper end thereof and projecting above the standard so that the table B is normally held against turning. When it is desired to turn the table B the latter is lifted to disengage 15 the pin P from the corresponding aperture B⁸, and in order to lift the table the operator presses the treadle L into lowermost position so that the upper terminal K' of the plunger K engages a depending pin B⁹ on the hub B' 20 to lift the latter and consequently the table B (see Fig. 7). It will be noticed that during this upward movement of the plunger K both the cam J³ and the catch N are pushed out of engagement with the standard A thus allowing 25 convenient turning of the table B and the parts supported thereby until the pin P is in register with any one of the apertures B⁸, after which the operator releases the pressure on the treadle L to lower the table 30 B and to engage the pin P with the registering aperture B⁸. The table is then again locked against rotation on the upper end of the standard A.

In order to fully move the cam J³ out of 35 the standard A during the lifting of the table B, the lever J² is provided with a shoulder J⁵ adapted to abut against an annular flange A⁴ formed exteriorly on the standard A near the upper end thereof. 40 Thus when the table is raised the shoulder J⁵ strikes the flange J⁴, thus swinging the lever J into outermost position as shown in Fig. 7. The lever J is provided at its lower end with a segmental treadle J⁶ adapted to cover the 45 openings A² not used at the time by the cam J³ (see Fig. 8), it being understood that the openings A² and the keepers A³ correspond to the number of the openings B⁸ and are similarly arranged so that when the table 50 B is turned the cam J³ engages the corresponding opening A² and the catch N engages the corresponding keeper A³.

The holder F for carrying the hat block G, shown in Figs. 1, 2, 4 and 5, is in the 55 form of a disk provided at its center with a nut F' (see Fig. 15) screwing on a screw F² secured in the center of a base F³, preferably of oval shape, and fitting into the oval opening of the offset E. The base F³ is provided at its bottom with a projecting pin F⁴ 60 adapted to engage a recess E' formed on the offset E (see Fig. 4), and diametrically opposite the pin F⁴ is arranged a nut F⁵ in which screws a screw E² screwing laterally 65 in the offset E. Thus by the arrangement described the base F³ can be readily fastened in place in the offset E. After the base F³ has been placed in position in the offset E, the holder F can be readily screwed on the screw F². The hat block G is fashioned according to the shape of the hat and its rim G' is adapted to be engaged with a series of pins Q disposed radially and mounted on upwardly extending arms Q' of slides Q² mounted to slide inward and outward on the 70 base G'. The inner ends of the slides Q² are connected by links Q³ with a center piece Q⁴ attached to the base G', and the slides Q² are connected with each other by chains Q⁵ passing over guide pulleys Q⁶ journaled on the 75 base G'. A screw Q⁷ screws in an upwardly extending lug F⁶ formed on the holder F and the inner end of this screw Q⁷ is mounted to turn loosely in the arm Q' of one of the slides Q². Thus by turning the screw 80 Q⁷ in one direction the corresponding slide Q² is moved outward to disengage its pin Q from the block G and the latter is now moved by the operator to the right to push the other two slides Q² outward, after which 85 the operator lifts the block off. The several slides Q² are now in approximately the position shown in Figs. 14 and 15. Another block is now placed in position and then the operator turns the screw rod Q⁷ in the opposite direction to move the corresponding slide Q² inward whereby the chains Q⁵ draw the other two slides Q² inward and engage 90 the pin Q with the rim G' of the inserted block G. It will be seen that by the arrangement described the base G' of the block G can be readily engaged with the pins Q while the slides are in outermost position, and then the screw Q⁷ is turned to move the slides Q² inward to firmly draw the several 95 pins Q in firm contact with the rim G' of the block G.

The hat block G, shown in Figs. 1, 2, 4 and 5, is more especially designed for flanging and finishing ladies' hats. When it is 100 desired to flange and finish men's hats, use is made of a hat block R such as shown in Figs. 16 and 17. The hat block R is of oval shape with an opening for the crown of the hat and with a rim shaped for giving the corresponding shape to the hat. In order to accommodate any height of crown in the block R, the latter is set on a base S of oval shape and set on top of the offset E and removably fastened thereto. The base S is provided with a depending annular arm S' adapted to engage the recess E' formed in the offset E, and the base S is provided diametrically opposite the arm S' with a hinged nut S² in which screws the screw E² 110 previously mentioned, to securely hold the base S in position on the offset E. The top of the base S is provided on one side with a pivoted upwardly and outwardly extending arm S³ adapted to engage a recess R' formed 115 120 125 130

in the under side of the block R. The arm S³ is provided with a stop S⁴ to limit the swinging movement of the arm S³ and to prevent accidental disengagement of the arm S³ from the recess R'. In the base S directly opposite the arm S³ screws a screw rod S⁵ having a handle S⁶ extending within an opening S⁷ arranged in the base S to allow of conveniently turning the screw rod S⁵. The upper end of the screw rod S⁵ screws into a nut R² attached to the under side of the block R to securely fasten the latter in position on top of the base S.

From the foregoing it will be seen that by 15 the arrangement described, hat blocks of various shapes and forms can be readily attached to the offset E of the carrier D and the latter can be readily turned with such block, and when either in a vertical or horizontal position, as previously explained, they enable the operator to readily flange and finish the hat on the hat block. It will also be noticed that whenever it is desired to change the carrier D from horizontal to 20 vertical position and vice versa, it can readily be done on the operator pressing the treadle L to automatically unlock the plate C and allow the operator to swing the parts from one position into the other. When it is desired to change the position of the table B it can readily be done by the operator pressing the treadle L to lift the table out of engagement with the pin P to permit of 25 turning the table and to then allow re-locking of the standard to the table, as previously explained.

From the foregoing, it will be seen that the operator has free use of his hands without requiring the same for locking or 30 unlocking purposes, and the hat blocks can be readily interchanged to enable the operator to flange and finish the hat. It will also be noticed that plaster casts, commonly called coolers, may be attached to the offset E of 35 the carrier D for flanging and finishing stamped hats without once removing the hat from such block.

The carrier D and the parts carried thereon may be rotated by hand or by power, and 40 whether the carrier is in horizontal or vertical position. When it is desired to rotate the carrier by power the offset E is used as a pulley (see Fig. 18) and a belt E³ connects this pulley with a pulley E⁴ secured on a 45 power driven shaft E⁵.

Having thus described my invention, I claim as new and desire to secure by Letters Patent:

1. A hat flanging and finishing machine, 50 comprising a standard, a table supported on the said standard, a plate mounted to swing on the said table to overlie the latter or to stand at a right angle to the table, a carrier mounted to turn on the said plate and having means for removably holding a

hat block, locking means for locking the said plate when in horizontal position to the table, locking means for locking the said table when in vertical position to the said standard, and releasing means adapted to 70 be controlled by an operator and mounted on the said standard for releasing either of the said locking means.

2. A hat flanging and finishing machine, 75 comprising a standard, a table supported on the said standard, a plate mounted to swing on the said table to overlie the latter or to stand at a right angle to the table, a carrier mounted to turn on the said plate and having means for removably holding a hat block, locking means for automatically locking the said plate to the said table on swinging the plate into horizontal position, and releasing means adapted to be controlled by 80 an operator and mounted on the said standard for releasing the said locking means.

3. A hat flanging and finishing machine, 85 comprising a standard, a table supported on the said standard, a plate mounted to swing on the said table to overlie the latter or to stand at a right angle to the table, a carrier mounted to turn on the said plate and having means for removably holding a hat block, locking means for automatically locking the said table to the said standard on 90 swinging the plate into vertical position, and releasing means adapted to be controlled by an operator and mounted on the said standard for releasing the said locking means.

4. A hat flanging and finishing machine, 95 comprising a standard, a table supported on the said standard, a plate mounted to swing on the said table to overlie the latter or to stand at a right angle to the table, a carrier mounted to turn on the said plate and having means for removably holding a hat block, locking means for automatically locking the said table to the said standard on 100 swinging the plate into vertical position, releasing means adapted to be controlled by an operator and mounted on the said standard for releasing the said locking means, and springs carried by the said table and adapted 105 to be compressed on swinging the plate into vertical position, the said springs on releasing the said locking device imparting a 110 swinging motion to the plate.

5. A hat flanging and finishing machine, 115 comprising a hollow standard, a table mounted on the said standard, a plate mounted to swing on the said table to overlie the latter or to extend in an upright direction, a carrier mounted to turn on the said plate, a hat block removably mounted on the said carrier, a fixed lug on the plate, a 120 slidable lug on the said plate diametrically opposite the fixed lug, the said slidale lug being adapted to engage the said standard to lock the plate in upright position, and a movable keeper on the said table adapted to 125 130

be engaged by the said fixed lug to lock the plate when in horizontal position to the said table.

6. A hat flanging and finishing machine, comprising a hollow standard, a table mounted on the said standard, a plate mounted to swing on the said table to overlie the latter or to extend in an upright direction, a carrier mounted to turn on the said plate, a hat block removably mounted on the said carrier, a fixed lug on the plate, a slidible lug on the said plate diametrically opposite the fixed lug, the said slidible lug being adapted to engage the said standard to lock the plate in upright position, a movable keeper on the said table adapted to be engaged by the said fixed lug to lock the plate when in horizontal position to the said table, and means adapted to be controlled by an operator mounted on the said standard and adapted to release the said slidible lug and to disengage the said keeper from the said fixed lug.

7. A hat flanging and finishing machine, comprising a hollow standard, a table mounted on the said standard, a plate mounted to swing on the said table to overlie the latter or to extend in an upright direction, a carrier mounted to turn on the said plate, a hat block removably mounted on the said carrier, a fixed lug on the plate, a slidible lug on the said plate diametrically opposite the fixed lug, the said slidible lug being adapted to engage the said standard to lock the plate in upright position, a pedal-controlled plunger mounted to slide up and down in the said standard and adapted to engage and release the said slidible lug, a slide on the table and controlling the said movable keeper, and a lever fulcrumed on the table and controlling the said slide, the said lever being controlled by the said plunger.

8. A hat flanging and finishing machine provided with a revoluble carrier provided on its face with a ring-shaped offset having a recess and having a screw, and a hat block holder having a lug adapted to engage the said recess and having a nut adapted to be engaged by the said screw to removably fasten the said holder to the said offset.

9. A hat flanging and finishing machine provided with a revoluble carrier provided on its face with a ring-shaped offset having a recess and having a screw, a hat block holder having a lug adapted to engage the said recess and having a nut adapted to be engaged by the said screw to removably fasten the said holder to the said offset, a hat block, and attaching means removably attaching the said hat block to the said holder.

10. A hat flanging and finishing machine provided with a revoluble carrier having on its face a ring-shaped offset provided with a recess and with a screw, a base fitting into

the opening of the offset, a lug on the base engaging the said recess, a nut on the said base adapted to be engaged by the said screw, a central threaded post on the said base, a platform having a central nut screwing on the said post, and retaining jaws adjustably held on the said platform for engagement with a hat block.

11. A hat flanging and finishing machine provided with a revoluble carrier having on its face a ring-shaped offset provided with a recess and with a screw, a base fitting into the opening of the offset, a lug on the base engaging the said recess, a nut on the said base adapted to be engaged by the said screw, a central threaded post on the said base, a platform having a central nut screwing on the said post, retaining jaws adjustably held on the said platform for engagement with a hat block, and manually controlled means for simultaneously adjusting the said jaws.

12. A hat flanging machine provided with a hat block holder comprising a platform, jaws mounted to slide radially on the said platform and adapted to engage the peripheral face of a hat block, links pivotally connecting the jaws with the platform, a nut on the platform, a screw screwing in the said nut and mounted to turn in one of the said jaws, and a connection between the said jaws to move the latter simultaneously inward on the platform according to the direction in which the said screw is turned.

13. A hat flanging and finishing machine provided with a revoluble carrier having on its face a ring-shaped offset provided with a recess and with a screw, a ring-shaped hat block base fitting onto the said offset and having a lug and a nut, of which the lug engages the said recess and into the nut screws the said screw, a ring-shaped hat block fitting onto the said base, and attaching means for attaching the block to the base at the contacting faces thereof.

14. A hat flanging and finishing machine provided with a revoluble carrier having on its face a ring-shaped offset provided with a recess and with a screw, a ring-shaped hat block base fitting onto the said offset and having a lug and a nut, of which the lug engages the said recess and into the nut screws the said screw, a ring-shaped hat block fitting onto the said base, a screw rod screwing in the said base, a nut on the said block and into which screws the said screw rod of the base, and a bell crank lever fulcrumed on the base and having one of its arms engaging the said block.

15. A hat flanging and finishing machine provided with a hollow standard, a table having a hub fitting into the upper end of the said standard, the table having apertures arranged in a circle concentric with the said hub, a locking pin on the said standard and engaging one of the said apertures to nor-

mally lock the table against rotation, and means on the said standard and adapted to be controlled by an operator to engage the said hub to lift the table until the latter is 5 disengaged from the said pin to allow of turning the table.

In testimony whereof I have signed my

name to this specification in the presence of two subscribing witnesses.

THOMAS J. MACDONALD.
